ATTORNEY.

UNITED STATES PATENT OFFICE.

HERBERT ABRAHAM, OF NEW YORK, N. Y., ASSIGNOR TO THE RUBEROID COMPANY,
A CORPORATION OF NEW JERSEY.

SELF-SPACING SHINGLE.

Application filed November 21, 1921. Serial No. 516,700.

To all whom it may concern:

Be it known that I, HERBERT ABRAHAM, a citizen of the United States, residing in the city, county, and State of New York, have 5 invented a certain new and useful Improvement in Self-Spacing Shingles, of which the following is a specification.

This invention relates to self-spacing shingles made of prepared roofing material.

10 In laying individual shingles it is usual to space them apart laterally. Accordingly it has been proposed to provide shingles which are so constructed that when laid side by side they will be automatically spaced. It has also been proposed to provide 15 guides on the shingles to indicate the extent of exposure to the weather when laid in overlapping courses.

The present types of self-spacing shingles provided with guides indicating exposure are so designed that they cannot be manufactured without loss or waste of material. This, of course, increases the cost of the shingles.

20 My invention aims to provide self-spacing shingles with guides indicating the proper exposure to the weather which are designed to be cut from a web or sheet of prepared roofing material without waste, and which 25 have other advantages hereinafter set forth.

30 In the accompanying drawings illustrating a preferred embodiment of the invention.

Figure 1 represents a portion of a web or sheet of roofing material, with the lines 35 for cutting the shingles indicated thereon.

Figure 2 shows two of the shingles as cut but slightly separated.

Figure 3 is a similar view showing the shingles positioned for use, and,

40 Figure 4 is a plan view of a section of roof laid with such shingles.

Referring to Figure 1 of the drawings it will be seen that the web or sheet is cut into series of complementary pairs of units 45 or shingles A and B, two of which are shown slightly separated in Fig. 2. Before laying, each alternate unit B is turned upside down in its own plane as indicated in Figure 3 so that the edges of the adjacent units A and B which were contiguous when 50 cut, will be remote when laid.

In cutting, each unit A is provided at the upper portion of one side with a projection 1 which is the complement of the recess 2 of the contiguous unit B, and which is substantially equal in width to the horizontal distance or slot 12 between the lower portions or butts of adjacent units when laid as shown in Figure 4.

Directly below the middle of each unit A 60 and on the same side as the projection 1 is a second projection 3. The act of cutting the projection 3 forms a projection 4 on the contiguous edge of the unit B and also forms a recess 5 in the lower portion of the 65 unit A, which recess has its complement in the projection 6 of the unit B.

While I prefer to have the projection 3 rectangular in configuration, it may be of other shapes. It is essential however, that 70 the lower corner 7 of the projection be spaced vertically from the lower edge of the unit a distance substantially equal to the vertical extent that the unit is intended to be exposed when laid as shown in Fig. 4, and 75 that said corner be spaced horizontally from the body of the unit a distance substantially equal to twice the width of the space or slot 12 between the lower portions of adjacent units when laid.

80 On the lower portion of each unit A and extending above the middle thereof, on the side opposite to that having the projections 1 and 3, is another projection 8. The projection 8 is similar in width to the projection 1 but is longer, extending upwards to a point opposite to the lower edge of the projection 1. The manner of cutting the projection 8 of the unit A, of course, forms a complementary recess 9 in the contiguous 85 unit B, and also forms a projection 10 on the upper part of said unit B, which projection is similar in dimensions to the projection 1 of unit A. It will be seen that the projection 10 is the complement of recess 11 90 of unit A.

95 The manner of cutting hereinabove described produces self-spacing shingles which can be formed without loss or waste of any material except that which must be trimmed 100 from the ends of the sheet in the cutting operation. Furthermore, such shingles can

be conveniently stacked, and packed in substantially rectangular shaped packages for shipment, by laying one on the other.

The units B are turned upside down in their own plane, as hereinabove mentioned and as shown in Fig. 3 to bring them into laying position. In laying a roof, the shingles are laid side by side in a row to form a course in which the units A and B alternate, and with similar courses successively applied thereon in overlapping relation as shown in Fig. 4; this being the usual method of laying such roofs. The units are fastened to the roof deck by nails 13, which are preferably positioned as indicated in Fig. 4. It will be observed that when the shingles are laid and fastened as shown, each unit is held down by two nails, one of which is driven directly into the unit, and the other of which penetrates through from the unit above. Furthermore, it will be seen that the nail heads of the shingles of each lower course are covered by the shingles of each upper course.

When laid as described, the projection 6 of each unit B fits into the recess 11 of the laterally adjacent unit A, and the projection 4 of unit B abuts against the edge of projection 8 of unit A, thereby automatically spacing said units the width of the slot 12. The unit pairs B—A are similarly spaced by abutment of the projection 3 of the unit A against the lateral edge of unit B directly above the shoulder between the projection 10 and recess 9 of the latter. It will be noted that a space or pocket is formed in the points between units B—A and A—B above the projections 3 and 4, respectively. Should the wind drive any water up beyond the top of the slot 12, the interposition of said space will prevent the water from traveling further along the joint.

What I claim is:

1. A pair of self-spacing prepared roofing elements adapted to be laid with other similar pairs in overlapping courses in simulation of a shingled roof, comprising elements each having two spaced projections of different widths on one lateral edge, and a single projection, corresponding in width to the narrower of the first mentioned projections, on the opposite lateral edge.

2. A pair of self-spacing prepared roofing elements adapted to be laid with other similar pairs in overlapping courses in simulation of a shingled roof, comprising elements each having two spaced projections on one lateral edge, one of said projections being double the width of the other, and a single projection corresponding in width to the narrower of the first mentioned projections on the opposite lateral edge.

3. A pair of self-spacing prepared roofing elements adapted to be laid with other similar pairs in overlapping courses in simula-

tion of a shingled roof, comprising elements each having two spaced projections on one lateral edge, the width of the base of one of said projections being equal to the width of the space between the exposed portions of the laterally adjacent elements when laid and the base of the other of said projections being double said width, and a single projection on the other lateral edge corresponding in width to the narrower of the first mentioned projections and forming a shoulder-seat for the wider projection of the next laterally adjacent element when laid.

4. A pair of self-spacing prepared roofing elements adapted to be laid with other similar pairs in overlapping courses in simulation of a shingled roof, comprising elements each having two spaced projections on one lateral edge, the width of the base of one of said projections being equal to the width of the space between the exposed portions of the laterally adjacent elements when laid, 70 the base of the other of said projections being double said width, the distance measured vertically from the lower edge of the element to the base of the lower of said projections being equal to the vertical extent that the element is intended to be exposed when laid, and a single projection on the other lateral edge corresponding in width to 75 the narrower of the first mentioned projections and forming a shoulder-seat for the wider projection of the next laterally adjacent element when laid.

5. Self-spacing prepared roofing element-pairs adapted to be cut without waste and to be laid in overlapping courses, with alternate elements of each course turned upside down, in simulation of a shingled roof, each element having two parallel straight sides 80 and two sides provided with projections, the projections on either side being the complements of the projections of the adjoining element in cutting position and forming 85 abutments for spacing adjacent elements in 90 the laying position.

6. Self-spacing prepared roofing element-pairs adapted to be cut without waste and to be laid in overlapping courses, with alternate elements of each course turned upside down, in simulation of a shingled roof, each element having two parallel straight sides 95 and two sides provided with projections, one of the latter having a single projection and the other a plurality of projections, the 100 complements of the projections of the adjoining element in cutting position and forming 105 abutments for spacing adjacent elements in 110 the laying position.

7. Self-spacing prepared roofing element-pairs adapted to be cut without waste and to be laid in overlapping courses, with alternate elements of each course turned upside down, in simulation of a shingled roof, each 115 120 125 130

element having two parallel straight sides and two sides provided with projections, one of the latter sides having a single projection of a width substantially equal to the width 5 of the space between the exposed portions of adjacent elements when laid, and the other having a plurality of projections one of which is double the width of the projection on the opposite side, the projections on either side being the complements of the projections of the adjoining element in cutting position and forming abutments for spacing adjacent elements in laying position.

HERBERT ABRAHAM.
